UNITED STATES PATENT OFFICE.

WILLIAM HENRY TAMS, OF TRENTON, NEW JERSEY, ASSIGNOR TO THE GREENWOOD POTTERY COMPANY, OF SAME PLACE.

DESIGN FOR A DISH.

SPECIFICATION forming part of Design No. 22,644, dated July 25, 1893.

Application filed March 7, 1893. Serial No. 485,048. Term of patent 7 years.

To all whom it may concern:

Be it known that I, WILLIAM HENRY TAMS, a citizen of the United States, residing at Trenton, in the county of Mercer and State of New Jersey, have invented and produced a new and original Design for Dishes, of which the following is a specification, reference being had to the accompanying drawing, illustrating the same.

10 My invention relates to a design for dishes. The accompanying drawing illustrates a dish having my design thereon.

15 The design comprises a series of decorative figures A arranged in proximity to the periphery of the dish or in the form of a circle and a decorative figure B in the center of such circular arrangement of figures. Each of the decorative figures A of the circular arrange-

ment comprises ornamental scrolls *a* composed of leaves and stems; decorated fan-shaped figures *b* where two stems or parts of the scroll work *a*, diverge; delicate stems and flowers *c* and small scrolls *d*,—these features being combined to produce a decorative design. The central figure B comprises a series 25 of decorative scrolls *e*, a scroll *f* and delicate stems and flowers *g*, all combined to produce a decorative design.

What I claim is—

20 The design for dishes herein shown and described.

WILLIAM HENRY TAMS.
